Patented Jan. 21, 1919.

INVENTOR.
W. B. MAY.

ATTORNEY.

UNITED STATES PATENT OFFICE.

WILLIAM B. MAY, OF DENVER, COLORADO.

PHONOGRAPH ATTACHMENT.

1,292,349.

Specification of Letters Patent. Patented Jan. 21, 1919.

Application filed July 10, 1917. Serial No. 179,649.

To all whom it may concern:

Be it known that I, WILLIAM B. MAY, a citizen of the United States, residing at Denver, in the county of Denver and State 5 of Colorado, have invented certain new and useful Improvements in Phonograph Attachments, of which the following is a specification.

This invention relates to phonograph attachments, and its primary object resides 10 in the provision of a brush of simple construction adapted to thoroughly clean the grooved face of a sound record while it is being revolved by the motor of the phonograph instrument to which it is attached.

With the above object in view, my invention comprises a brush made of any suitable material, which is connected with a spring 15 to receive a gentle downward pressure for 20 its frictional contact with the record.

The spring is mounted upon the casing or motor-box of the instrument, and is rotatable about an upright axis for its adjustment to move the brush into and out of contact with the face of a record supported 25 upon the revolving table of the phonograph.

The brush is pivoted on the spring for its self-adjustment to follow the usual wobble of the record, and its pivotal axis is preferably arranged nearer its forward end to cause it to tilt when it is separated from the record, and thereby facilitate its subsequent movement onto the face thereof.

An embodiment of my invention is illustrated in the accompanying drawings in the several views of which like characters of reference refer to corresponding parts and in which

Figure 1 represents a fragmentary perspective view of a phonograph to which my attachment is applied,

Fig. 2, a fragmentary plan view of the phonograph showing the attachment in its operative position with relation to a sound-45 record supported thereon,

Fig. 3, a view similar to Fig. 2 showing the attachment in its idle or inoperative position,

Fig. 4, a section taken along the line 4-4, 50 Fig. 2, drawn to an enlarged scale, and

Fig. 5, an enlarged transverse section on the plane indicated by the line 5-5, Fig. 4.

The reference character 2 designates the motor-box or casing of a phonograph instrument, 3 the revolving record-supporting table thereof, and 4 the sound-box which at the end of a pivoted arm 5, carries the stylus 6 traveling through the groove of a record-disk 7 supported upon the table 3.

My attachment consists of a base-plate 8 secured upon the top of the casing by means of screws or other fastening devices.

The plate carries an upright spindle 9 which is threaded at its upper end for the reception of a tension nut 10. A C-spring 65 12 has adjacent its bow two aligned openings to admit the spindle for its pivotal support upon the base plate, the nut 10 engaging the upper surface of the spring to regulate its tension.

The arms of the spring are of uneven length, the upper one 13 being sufficiently long to project over the revolving table of the instrument to which the attachment is applied.

Pivots suspended from the end of the arm 13 is the record-cleaning brush 14 which is made of elongate form to traverse the grooved side of the face of a record-disk supported on the table.

The brush in its preferred form, is made of a wooden core 15 covered with plush or other material, 16, suitable to enter the sound grooves of the record, and longitudinally grooved to receive opposite edges of 85 a metal holder 17 of channel section to which it is attached.

The connection of the brush with the arm of the spring 13 which is curved to permit of a limited pivotal motion of the same, is 90 established through the instrumentality of a U-shaped yoke 18 secured to the spring and straddling the brush.

A bolt 19 secured in aligned openings of 95 the yoke extends loosely through openings in the sides of the holder and a corresponding space in the core to provide the pivot about which the brush may move to adjust its position in accordance with the transverse slant of the record.

The pivot is, as hereinbefore explained, arranged nearer to the forward end of the brush so that when the attachment is in its inoperative position as shown in Fig. 3, the

brush which in this position is separated from the record, will slant from its rear end upwardly to facilitate its moving onto the face of the record when the spring is subsequently moved about its pivot to bring the brush into the operative position with relation thereto.

10 A stop 20 on the base plate determines the two adjusted positions of the spring, by engaging the short lower arm thereof, and a pad 21 secured to the end of the long arm of the spring cushions the upward movement of the brush, principally for the purpose of eliminating noise.

15 The operation of the attachment will be readily understood from the above description of its construction.

When the brush is not in use, it is in the position shown in Fig. 3, tilting slightly 20 upwardly to facilitate its movement onto the face of a record supported upon the revolving table of the phonograph instrument.

25 When it is desired to clean the record, the spring is moved about its pivot until its short arm engages the stop 20 and the brush extends transversely of the grooved side of the record as shown in Figs. 1 and 2.

30 The soft material covering the core of the brush, enters the sound grooves of the record and thoroughly cleans the same from dust and other foreign matter by the rotary movement of the same, it being understood that the spring presses it gently into frictional contact with the record and that its 35 pivotal connection with the spring permits of its following every deviation of the record from the plane in which it has its rotary movement.

40 The nut at the end of the spindle provides ready means to vary the pressure of the brush upon the face of the record, and to change the position of the same in accordance with the height of the record above the top of the casing upon which the attachment is mounted through the medium of the base-plate.

Having thus described the construction and operation of my improved phonograph brush in the best form at present known to 50 me, I desire it understood that variations in the construction and arrangement of the parts thereof, may be resorted to within the spirit of the invention as defined in the following claims.

55 1. An attachment for phonographs comprising a base having means for its attachment to the motor-box of a phonograph instrument, a resilient arm pivotally mounted thereon, and a brush pivotally connected 60 at an end of said arm for self-adjusting engagement with a horizontally moving surface.

2. An attachment for phonographs comprising a base having means for its attach-

ment to the motor-box of a phonograph- 65 instrument, an arm projecting therefrom, and a brush pivotally connected at the free end of said arm to tilt about a transverse axis.

3. An attachment for phonographs comprising a base having means for its attachment to the motor-box of a phonograph instrument, a projecting arm pivotally mounted thereon, and an elongate brush connected at the free end of said arm for movement 75 about a pivot nearest its forward end.

4. An attachment for phonographs comprising a base having means for its attachment to the motor-box of a phonograph instrument, a resilient arm projecting therefrom, means to regulate the resiliency of said arm, and a brush connected at the free end of the same.

5. An attachment for phonographs comprising a base having means for its attachment to the motor-box of a phonograph instrument, an upright spindle thereon, a C-spring pivotally mounted on said spindle and having a projecting arm, and a brush connected at the free end of said arm. 85 90

6. An attachment for phonographs comprising a base having means for its attachment to the motor-box of a phonograph instrument, an upright spindle thereon, a C-spring pivotally mounted on said spindle 95 and having a projecting arm, and a brush connected at the free end of said arm for movement about the transverse pivot.

7. An attachment for phonographs comprising a base having means for its attachment to the motor-box of a phonograph instrument, an upright spindle thereon, a C-spring pivotally mounted on said spindle and having a projecting arm, a brush connected at the free end of said arm, and an 100 adjustable nut on the spindle, engaging the upper surface of the same.

8. The combination with a phonograph instrument including a motor-casing and a revolving table above the top thereof, of a 110 resilient arm pivotally mounted upon said top, and a brush pivotally connected with said arm to engage a phonograph record supported on said table.

9. The combination with a phonograph instrument including a motor-casing and a revolving table above the top thereof, of an arm pivotally mounted upon said top, and a brush pivotally connected with said arm to engage a phonograph record supported on 115 said table. 120

10. The combination with a phonograph instrument including a motor-casing and a revolving table above the top thereof, of an arm mounted upon said top, and a brush 125 pivoted on the arm to tilt about a transverse axis and disposed to engage a phonograph record supported on said table.

11. The combination with a phonograph instrument including a motor casing and a revolving table above the top thereof, of a brush mounted to yieldingly engage a disk-
5 record on said table, and pivoted for self-adjustment in a plane transverse to that in which the table has its movement.

In testimony whereof I have affixed my signature in presence of two witnesses.

WILLIAM B. MAY.
